Marcus Merriman, New Haven, New Haven County, Conn.

U. S. Patent

The schedule referred to in this Patent and making part of the same containing a description, in the words of the said Marcus Merriman, of his Improvement in the Spring Bolt for fastening Window Sashes and doors, and for other purposes.

To all to whom these presents shall come, Be it known that I, Marcus Merriman, of New Haven in the County of New Haven in the State of Connecticut, have invented a new and useful Improvement in the Spring bolt for fastening Window Sashes, & doors and for other purposes, and that the following is a full & exact description thereof. My improved Spring bolt consists of the following parts viz. The bolt and thumb piece with a spiral spring in connexion therewith and a Concave Zinc Cylinderical Shell covering the Spring & bolt in such a way

that they are all made of brass or any other durable metal & may vary proportionally in dimensions to suit the uses in length according to the use intended. The piece for ordinary sash fastening requires a shell of about one and an half inches in length. The shell is closed at both ends except an orifice in one end for the head of the bolt & in the other for the shank of the bolt to play in. On the sides of the shell are flanges with holes for screws to secure it in place. On the top of the shell is a groove for the neck of the thumb piece to slide in commencing the thickness of the shell back of the point & extending back as far as the head of the bolt projects.

The groove then turns at right angles & forms a notch for the neck of the thumb piece. Made a little hollowing toward the front. The bolt is as much longer than the shell as it projects beyond it. The head is made round terminating in a shank of half size, and of about half the length of the bolt; when the bolt is in place, it plays into the orifice in the end of the shell. On the shank of the bolt is placed a spiral spring which by passing between the end of the bolt and the shoulder of the head projects it forward till checked by the neck of the thumb piece at the end of the groove.

In such a spring loosely through the gunne is firmly directed to the bolt so as
merely to resist the expansion of the spring and projection of the bolt.

The object intended and effected by this
improvement is that when the bolt is drawn back & the neck of the barrel
piano is turned into the notch it is there held fast by the force of the spring
not unlocked. This bolt is particularly adapted to fasten window dashes
when shut & in place. Being attached to the top part of the lower dash-plate
the bolt retaining a bolt of similar shape with the slot in the top of the
lower part of the upper dash bolt are made fast & by locking the bolt back
in the Notch of the gunne, not above described, both dashes are fast to remain
retained without obstructing from the bolt. For further illustrations refer
to the Models & drawings thereof deposited in the Patent office.

That of Clavis at my insertion and are
specially known is the application of the side Notch & spiral Spring which
the combination of the several parts, in the manner used for the purposes
above specified: By means of which a spiral spring bolt when drawn
back may be readily & easily locked & turned in place & therefore
obviates Sellers Patent, April 22nd 1831.
